UNITED STATES PATENT OFFICE.

HERBERT D. HOUGH, OF CRANSTON, RHODE ISLAND, ASSIGNEE TO WIGHTMAN AND HOUGH COMPANY, A CORPORATION OF RHODE ISLAND.

COIN-HOLDER

1,119,511.

Specification of Letters Patent.

Patented Dec. 1, 1914.

Application filed April 16, 1914. Serial No. 832,154.

To all whom it may concern:

Be it known that I, HERBERT D. HOUGH, a citizen of the United States, residing at Cranston, in the county of Providence and State of Rhode Island, have invented certain new and useful Improvements in Coin-Holders, of which the following is a specification.

My invention relates to coin holders. In this class of articles it has heretofore been necessary to stack the coins one above the other, which has resulted in making the casing inclosing the same unduly thick, and it is an object of this invention to overcome this defect.

Further objects of this invention are to house a maximum of coins in a minimum of space; to expose the coins in the holder without detracting from security; to insure the housed coins against accidental escape; to prevent the wear or abrasion of the plate beneath the coins; to cheapen the construction of the device, and facilitate the assemblage of the parts.

To the above ends essentially my invention consists in novel parts and combinations of parts hereinafter set forth and made the subject matter of the appended claims.

In the accompanying drawings which form a part of this specification, and in which like reference characters indicate like parts throughout the views, Figures 1 and 2 are side and front views respectively of a holder embodying my invention, Fig. 3, a front elevation of the same with the covers distended, Fig. 4, a section on line x, x , of Fig. 1, Fig. 5, a top end elevation of the holder member, Fig. 6, a section of the same on line y, y , of Fig. 5, and Fig. 7, an enlarged section on line z, z , of Fig. 6.

In its present and preferred form of embodiment my holder comprises two hollow covers or wings 1 and 2 provided respectively with inturned marginal flanges 3 and 4, and having respectively at their adjacent margins integral sleeves 5 and 6 embracing a pintle 7, and constituting a hinge. The central margin of the flange 3 is provided with a curved recess 10 and an adjacent slot 11. Integral with or fixed to the central portion of the flange 4 is a tube 13, in which is slidably mounted a plunger 14 having an enlarged base 15 provided with inclined projections 16. The base rests upon a flat spring 17 soldered or otherwise fixed

at its ends to the cover 2. When the covers are closed the tube 13 registers in the recess 10, and the projections 16 enter the slot 11 and engage the rear of the flange 3. The above described fastening means is not exclusive.

The holder member in the present instance is shown in conjunction with the described casing and in detail comprises a frame or plate 20 whose center is open, as at 21, and is provided upon one side margin with integral lugs 22 having their ends bent to form sleeves 23 engaging the pintle 7. Integral with the other side margin is a lateral lug 25 to whose upper end is soldered an ornament 26. This plate and the lugs are stamped or cut from a single sheet of thin metal. The flange 4 is cut away to form a recess 28 adapted to receive the member 25 when the covers are closed. The ornament 26 projects exterior of the covers or casing. A rectangular retaining plate 30 has an inturned marginal flange 31 around its periphery whose free edge is attached by solder to the margins of the plate 20. The plate 30 is provided with two longitudinally disposed oblong openings 32 and 33, the latter preferably narrower than the former. In alignment with these openings the flange or wall 31 at its upper portion is provided with oblong slots 35 and 36, the latter broader than the former.

Resting upon the front face of the plate 20 so as to close the opening 21 is a backing strip 38 in the present instance of celluloid, adapted to receive a memorandum, but this strip may if desired be omitted. Resting against this strip, or against the plate 20 when the strip is omitted is the outer margin of a back plate 40. This plate is cut and bent by suitable tools from a strip of thin resilient metal. It is provided at its center with a forwardly directed broad longitudinal rib 41 provided, if desired, with one or more perforations 43 adapted to receive a drop of solder 44 to unite the plates 30 and 40 after assemblage, if desired. The rib 41 is provided upon its opposite sides with longitudinally disposed shoulders 46 and 47; and the side margins of the plate 40 have forwardly directed longitudinal shoulders 49 and 50. The shoulders 49 and 46 are preferably nearer the plate 30 than are the shoulders 47 and 50, and all form guides for the coins which pass thereover, preventing the coins from touching the plate

40 whose front face is preferably of precious or plated metal, and exposed to the observer through the openings 32 and 33.

It will be observed that the rib 41 divides 5 the coin holding member or leaf into two oblong coin pockets 52 and 53 to which access is given by the coin slots 35 and 36. In order to prevent the accidental escape of coins through these slots the plate 40 is 10 provided with integral teats or projections 55 and 56 beneath the plate 30 and in longitudinal alinement with the center of the slots 35 and 36 respectively.

Suspension rings 57, and 58 may be soldered 15 to the upper margin of the cover 2 if desired.

In the present instance there is fixed to the frame 20 adjacent the flange 31 by solder two tubes 60 in alinement with each 20 other adapted to holding a pencil 62.

It will be observed that the resultant structure has a capacity for accommodating a large number of coins within a small area; that the character of the construction of the 25 coin holding member is such as to lend itself to a facile formation and assemblage of parts and at a small expense; that the travel of the coins upon the longitudinal guide ribs protects the surface of the plate beneath; that the projections intermediate the plates adjacent the coin slots afford in conjunction with the resiliency of the back plate a means for permitting the passage of 30 coins of different thicknesses resultant from different degrees of wear; and that the pencil and backing strip afford a convenient 35 means for notation.

What I claim is,—

1. In a coin holder, the combination of a 40 casing comprising covers, a pintle connecting the covers, a coin holding member comprising a back plate mounted on the pintle, and a front plate attached to the back and spaced therefrom to form a coin pocket, said 45 back plate being provided with marginal elevated guide shoulders.

2. In a coin holder, the combination of a 50 casing comprising covers, a pintle connecting the covers, a coin holding member comprising a back plate mounted on the pintle, and a front plate attached to the back plate and spaced therefrom to form a coin pocket, said back plate being provided with guide 55 shoulders spaced from the front plate.

3. In a coin holder, the combination of a 60 casing comprising covers, a pintle connecting the covers, a coin holding member mounted upon the pintle and provided with oblong coin pockets, said coin holder being provided with longitudinally disposed guide shoulders in the pockets.

4. In a coin holder, the combination with the covers and pintle, of a coin holding

member comprising a frame mounted upon the pintle, a front plate, a marginal flange 65 upon the front plate fixed to the margin of the frame said plate being provided with coin slots, and a back plate resting against the frame, provided with a rib in contact with the front plate forming coin pockets 70 in alinement with the coin slots.

5. In a coin holder, the combination with the covers and pintle, of a coin holding member comprising a frame mounted on the pintle, a front plate, a marginal flange 75 upon the front plate fixed to the frame said plate being provided with coin slots, and a back plate upon the frame, provided with a rib in contact with the front plate forming coin pockets in alinement with the coin slots, 80 said rib being provided with longitudinal disposed shoulders, and the back plate being provided with similar shoulders spaced from the first mentioned shoulders.

6. In a coin holder, the combination with 85 the covers and pintle, of a coin holding member comprising a frame mounted upon the pintle, a front plate, a marginal flange upon the front plate fixed to the margin of the frame, said plate being provided with 90 coin slots, a back plate resting against the frame, provided with a rib in contact with the front plate forming coin pockets in alinement with the coin slots, and a backing strip intermediate the frame and back plate. 95

7. In a coin holder, the combination with the covers and pintle, of a coin holding member comprising a frame mounted on a pintle, a front plate, a marginal flange upon the plate fixed to the frame said plate 100 being and provided with coin slots, a back plate upon the frame, tubes upon the frame adjacent the flange, said plate being provided with a rib forming coin pockets in alinement with the coin slots, and a locking 105 strip intermediate the frame and the back plate.

8. In a coin holder, the combination with the covers and pintle, of a coin holding member comprising a frame mounted upon 110 the pintle, a front plate, a marginal flange upon the front plate fixed to the frame and provided with coin slots, a back plate resting against the frame, an intermediate portion of the back plate being provided with 115 a rib fixed to the front plate forming coin pockets in alinement with the slots, and provided with projections beneath the front plate adjacent the coin slots.

In testimony whereof I have affixed my 120 signature in presence of two witnesses.

HERBERT D. HOUGH.
